UNITED STATES PATENT OFFICE.

HENRY N. CASE, OF OAK PARK, ILLINOIS, ASSIGNOR TO SEARS, ROEBUCK AND CO., OF CHICAGO, ILLINOIS, A CORPORATION OF NEW YORK.

METHOD AND APPARATUS FOR MAKING OVERLAY AND UNDERLAY PAPER.

Application filed March 5, 1919. Serial No. 280,750.

To all whom it may concern:

Be it known that I, HENRY N. CASE, a citizen of the United States, residing at Oak Park, in the county of Cook and State of Illinois, have invented certain new and useful Improvements in Methods and Apparatus for Making Overlay and Underlay Paper, of which the following is a specification.

10 This invention relates to the manufacture of paper coated on both sides with material capable of being etched to produce reliefs suitable for use as matrices in subjecting printing plates to the McKee process. Great difficulty has heretofore been experienced in providing the paper base with coatings of uniform thickness and in handling the wet, coated paper.

20 One object of this invention is to devise a method for producing a high grade coated paper of great uniformity.

25 Another object of this invention is to provide an apparatus by means of which the difficulties heretofore encountered are obviated and a high-grade product obtained.

In the accompanying drawings, Figure 1 is a view of an apparatus embodying the features of my invention. Fig. 2 illustrates a clamp employed in the manufacture of the paper. Fig. 3 is a sectional view taken approximately in the plane of dotted line 3 of Fig. 5. Fig. 4 is a view of a winding drum comprised in the apparatus. Fig. 5 is a transverse sectional view taken in the plane of line 5-5 of Fig. 3.

30 The paper to be coated may be of any suitable width, as, for example, eighteen inches, and is preferably supplied in the form of rolls of convenient diameter. In Fig. 1, A represents a roll of paper to be coated, the core of said roll having journals or trunnions A' which are rotatably supported in any suitable way, as, for example, in brackets 1 attached to a suitable fixed support 2. 3 is a guide roller on the support 2.

35 Means is provided for unwinding paper from the roll A and for drawing the paper through a bath of suitable coating material. While various constructions may be employed, I have herein shown a tank 4 which is divided into two compartments 5 and 6 by means of a vertical partition 7. In the lower portion of the partition 7 is an opening 8 which establishes communication be-

tween the two compartments. The tank 4 is filled by pouring the coating material into the compartment 6. 4^a is a drain opening in the tank 4 for use in draining or cleaning the tank, said opening being normally closed by a plug 4^b. Any suitable means may be provided for heating the contents of the tank 4. Herein I have shown the tank as located within a tank 9 capable of holding a suitable quantity of water, the water being heated by any convenient means, as, for example, an electric heater 9^a of common construction.

40 10 is a frame or rack adapted to stand in the tank 4. Within the lower portion of the rack 10 is rotatably mounted a roller 11. It is desirable that the roller 11 be as light as possible and that it turn very freely in its bearings. 11^a is a lock of any suitable construction for locking the roller 11 against rotation at will. Above and at one side of the roller 11 is a smaller roller 12. 12^a indicates a lock of any desired character for holding the roller 12 against rotation at will. The web of paper unwound from the roll A passes over the guide roller 3, thence over the upper edge 80 of the partition 7, thence into contact with the roller 12, and thence around the roller 11, the end of the web being secured in a clamp 13 of any suitable construction. The form of clamp herein shown comprises two 85 bars 14 faced with suitable material, as, for example, strawboard 15, said bars being clamped at opposite sides of the end portion of the web by means of screws 16 and wing nut 17. To one of the bars 14 is secured a suspending loop 18. 10^a are brackets on the rack 10 to support a clamp 13.

45 The means for drawing the web through the tank 4 comprises two cables 19 and 20 secured at their ends to a winding drum 21 and oppositely wound upon the drum. The drum is rotatably mounted in suitable bearings upon the support 2 and is adapted to be driven at relatively low speed by any suitable means, as, for example, the pulleys 100 22 and 23, belt 24, worm drive 25, pulleys 26 and 27, and belt 28, the pulley 27 being fixed to the armature shaft of a reversible electric motor 29. 30 indicates a device of standard construction for starting, stopping and reversing the motor. Each of the cables 19 and 20 extends over a guide pulley 31 secured to a suitable overhead sup-

port, the pulleys 31 being located side by side and preferably slightly forward of the side and preferably slightly forward of the tank 4. (Only one of the pulleys 31 is shown in the drawings.) To the free ends of the 5 cables 19 and 20 are connected weights 32 and 33, respectively, each weight having a hook to engage the loop 18 of a clamp 13. When one of the weights is adjacent to the tank 4, the other weight is adjacent to the 10 pulleys 31. Any suitable means may be employed to exert a slight braking effect upon the roll A, as, for example, a weighted bar 34 resting upon the periphery of the roll.

Assuming the parts to be in the position 15 shown in Fig. 1, the operation is as follows: The motor 29 is energized to cause the clamp 13 to be drawn up to the ceiling, the rate of travel being uniform and relatively slow, as, for example, thirty inches per minute, in order that the drainage of surplus coating from the paper shall be uniform. As the weight 32 rises, the weight 33 descends. Inasmuch as the pulleys 31 are forward of the tank 4, the descending weight 20 does not come into contact with the ascending coated paper. When the weight 32 has nearly reached the pulleys 31, the motor 29 is stopped; the lowered weight 33 and cable 20 are held out of the way of the operator in 25 any suitable manner, and a clamp 13 is placed upon the web, the ends of the clamp resting upon the brackets 10^a. The web 30 is then cut just above the last mentioned clamp, except for about one-fourth of an inch at one edge; and the coated strip hanging from the first mentioned clamp 13 is removed by unhooking the loop 18 of said clamp from the weight 32, the uncut portion of the strip tearing as the operator disengages the loop from the weight. A long 35 pole may be used to disengage the loop 18 from the weight 32. The coated strip is then suspended by engaging the loop 18 with a hook (not shown) fastened to the ceiling or other suitable overhead support.

After the coated strip has been removed as just described, the weight 33 is connected to the loop 18 of the clamp 13 which is resting upon the brackets 10^a, and the motor 50 29 is set in reverse operation, whereby the cable 20 is wound up and the cable 19 unwound. When the end of the web has been drawn up to the ceiling, another clamp 13 is placed upon the web adjacent to the brackets 10^a, and the coated portion removed as before described.

With narrow paper, it is desirable that 55 both rollers 11 and 12 be locked against rotation, particularly when the paper is deeply wire-marked. When the paper is over twelve inches wide, the roller 11 should be permitted to rotate freely. With a web more than eighteen inches wide, both rollers 60 11 and 12 should rotate.

65 The wiping action of the stationary sub-

merged rollers upon the paper is desirable, and as much of such wiping should be employed as is practicable. However, the passage of the web over a stationary roller places tension upon the web, and this factor 70 limits the amount of wiping that can be permitted to occur. The wider the web the less tension should be placed upon the submerged portion of the web, in order to prevent the formation of longitudinal streaks 75 from wrinkling, due to expansion of the paper when wet. Also the thinner the paper, the less must be the tension.

The brake 34 is used only when the weight of the roll A has been materially reduced. 80

When beginning operations, the rollers 11 and 12 are warmed by placing the rack 10 adjacent to any convenient source of heat, after which the rack is laid on the tank 4. The web is then drawn through the space 85 between the rollers and a clamp 13 secured to the end of the web. The rack is then carefully placed in the compartment 5, the lowered cable connected to the clamp, and the motor is started.

In order to prevent the formation of small pits in the coating, it is necessary to keep the coating material free from particles of lint, greasy particles, or particles not necessarily greasy but not easily wet by water. 95 The grinder, the coating machine, and all utensils must be kept free from oil, grease and other substances not readily miscible with water.

In handling a coating high in sizing, it is 100 difficult to prevent foaming. The difficulty may, however, be obviated or cured by avoiding violent agitation, by repeated skimming, and by using two compartments in the coating machine so that the compartment in which the paper is coated receives its supply from the bottom of the compartment into which the coating is poured.

To prevent variations in the thickness of the coating, which manifest themselves in 110 horizontal streaks, it is necessary that the paper be drawn through the bath at a uniform rate. If the paper be drawn through the bath too rapidly, streaks will form in 115 all directions.

The paper may be dried in any suitable way, after which it is cut into sheets of convenient size, as, for example, 12 x 18 or 17 $\frac{1}{2}$ x 22 $\frac{1}{2}$. The sheets are then calendered in any suitable manner, as, for example, by 120 means of the plating method, a number of sheets being placed between zinc plates, and the whole run back and forth between two large cylinders under great pressure.

The coating process herein disclosed produces a paper which is coated on both sides with a smooth, etchable coating of uniform thickness, and which will not shrink after 125 etching.

While I have herein referred to the paper 130

as adapted for use in making McKee matrices, it will be understood that the paper has various other uses.

It is to be understood that the invention is not limited to the constructions herein described, and that the dimensions, speed of operation and other quantitative features of the disclosure are merely illustrative.

I claim as my invention:

- 10 1. A web-coating machine having, in combination, a tank to contain coating material, web-guiding means submerged in the coating material, two cables, winding means arranged to wind and unwind both cables, one 15 cable being unwound as the other is wound, each of said cables having means to engage the web, and overhead guiding means for the cables, said cables being arranged alternately to draw the end of the web to an 20 elevated point.

2. A web-coating machine having, in combination web coating means, two cables, winding means arranged to wind and unwind both cables, one cable being unwound 25 as the other is wound, each of said cables having means to engage a web and said cables being arranged alternately to draw the end of the web to an elevated point, the motion of said web operating to coat the 30 same.

3. A web-coating machine having, in combination, a tank to contain coating material, a partition dividing said tank into two compartments, said partition having an opening 35 in its lower portion establishing communication between the two compartments, a removable frame having spaced supports adapted to stand submerged in one of said compartments, and a plurality of web guiding rollers journaled in the submerged portions 40 of said supports.

4. A web-coating machine having, in combination, a tank to contain coating material, a removable frame supported upon the floor 45 of said tank, and web-guiding means and a clamp support carried by said frame.

5. A web-coating machine having, in combination, web-coating means, and two devices arranged to reciprocate in opposite directions and each arranged to engage the end of the web to draw the end of the web to an elevated point, the elevation of the end of the web operating to coat the web.

6. The method of coating a strip of material which comprises moving the strip into and out of a bath of coating material and

pressing against the strip first on one side and then on the other while it is submerged in the bath, as much of said pressure as the tensile properties of the strip will allow being accomplished by rubbing contact and the remainder being accomplished by rolling contact.

7. A unitary container for a coating bath comprising two compartments having an intercommunicating passageway adjacent their lower ends, one of said compartments having a plugged opening for facilitating the emptying and cleaning of said container.

8. A web coating machine having, in combination, a tank to contain coating material, a removable frame supported upon the floor of said tank, and web guiding means carried by said frame.

9. A web coating machine having, in combination, a tank to contain coating material, a partition dividing said tank into compartments, said partition having an opening in its submerged portion establishing communication between the two compartments, a removable frame adapted to stand submerged in one of said compartments, a web guiding roller journaled in said frame, and locking means for preventing said roller from rotating as the web to be coated passes through the machine.

10. A web coating machine having, in combination, a tank to contain coating material, a partition dividing said tank into two compartments, said partition having an opening in its submerged portion establishing communication between the two compartments, a removable frame having spaced supports adapted to stand submerged in one of said compartments, and a web guiding roller journaled in the submerged portions of said supports.

11. In the manufacture of overlay and underlay paper, the method of coating a strip of paper which comprises moving the strip into and out of a bath of coating material and pressing the coating material against the strip while the latter is submerged in the bath, as much of said pressure as the tensile properties of the strip will allow being accomplished by rubbing contact and the remainder being accomplished by rolling contact.

In testimony whereof, I have hereunto set my hand.

HENRY N. CASE.
